Patented July 9, 1912.

UNITED STATES PATENT OFFICE.

ALICE W. FALLON, OF CINCINNATI, OHIO.

CIGAR-BOX.

1,032,053.

Specification of Letters Patent.

Patented July 9, 1912.

Application filed March 25, 1912. Serial No. 885,918.

To all whom it may concern:

Be it known that I, ALICE W. FALLON, a citizen of the United States, residing at Cincinnati, in the county of Hamilton and State of Ohio, have invented certain new and useful Improvements in Cigar-Boxes, of which the following is a specification.

The object of my invention is to produce an extremely simple and inexpensive device which is adapted to be conveniently and easily operated to adjust the cigars from one position to another within the box without removing them therefrom so that the upper layer of cigars in the box will always be maintained near the top edge thereof to give it the appearance of a newly or recently opened box, thus rendering it practical for the manufacturer to equip every box of cigars with one of these devices before the cigars are placed therein.

My invention consists in the combination with a cigar box having a series of upwardly tapered notches in the sides thereof, of an adjustable bed or support the edges of which are flanged or bent downwardly, said bed being adapted to fit the inside of said box and having elongated slots in two of the flanged edges of said bed through which a ribbon or tape is adapted to pass, spring wires each fastened at its middle point on the under side of said bed adjacent the ribbon or tape, said wires running parallel to said ribbon or tape and bent at right angles near each end of the bed to form extending ends, said ends projecting through the flanged edges of said bed and projecting beyond same and slightly bent upwardly and inwardly at their ends to form resilient engaging catches for the sides and notches of said box.

My invention further consists in the details of construction and in the combination of parts as herein set forth and claimed.

In the drawings, which serve to illustrate the construction and application of my invention: Figure 1 is a perspective view of a cigar box equipped with my invention, part of the casing of which is broken away for the sake of clearness; Fig. 2 is a vertical section taken through a cigar box equipped with my invention; Fig. 3 is a perspective bottom view of the adjustable bed; Fig. 4 is a vertical section of a portion of one of the notched sides of the box showing a spring catch firmly supported in one of the notches.

In the embodiment of my invention as

illustrated and which shows a preferred construction, 1 represents a cigar box or casing which may be of any desired construction having a lid 2 hinged thereto. The front and rear sides 3 of the box are provided with a series of notches 4 having upwardly tapered or beveled sides 5. These notches are preferably provided one above the other adjacent the edges of the front and rear sides 3 of the box. A bed preferably of metal 6 is provided and is adapted to slidably fit the inside of said cigar box 1. This bed is stamped with flanged edges 7, 7 and 8, 8, said flanges being provided for the purpose of forming suitable bearings for the spring wire catches to be hereinafter described and to strengthen and add to the appearance and finish of the bed. A slot 9 is provided in each of the flanges 7 through which a ribbon or tape 10 is adapted to pass. The purpose of the ribbon 10 is to provide convenient lifting means whereby the cigars may be tied after they have been properly packed in the box. Fastened on the bottom of said bed 6 are two spring wires 11 which are fastened preferably by means of a drop of solder 12 in proximity to the center of the bed. These wires 11 run parallel with the ribbon or tape 10 from each side of the drop of solder to points near the flanges 7 of the bed 6 where they are bent at right angles and pass through suitable openings in the flanges 8 thereby forming four projecting resilient supporting catches 13 for the bed. These catches 13 are preferably bent upwardly and inwardly as shown at 14 to form more suitable engaging catches. Owing to the fact that the wires 11 are fastened only at their middle point the ends of same forming the catches 13 will be resilient allowing the bed to be elevated very easily to the position desired but forming a secure bed for the cigars against being forced downwardly beyond the notches 4.

It is evident that the construction of the bed 6 is extremely simple and inexpensive to manufacture and it is these qualities that make the device a most practical one for the purposes set forth.

The operation of the device is as follows: After the cigar box has been equipped with the adjustable bed, the cigars properly packed therein and the ribbon tied preferably in a bow at the top thereof and the box is shipped to the retailer who upon opening the lid unties the ribbon and places the box

in a show case with the ribbons extending down the sides thereof where they will not be in the way. As the box becomes emptied of its cigars, say for instance about two 5 layers having been sold, the bed is gently elevated or lifted by means of the ribbons or tape 10 to the first set of notches 4 where the catches 13 will immediately engage said notches and form a firm bed for the remaining 10 cigars in the box. The cigars are now level with the top of the box and the box appears as if filled with cigars. The same operation is repeated when the level of the 15 cigars falls down far enough to again warrant the raising of the bed.

While my invention is specially intended and adapted for use in cigar boxes it is also capable for use for elevating the contents of other boxes in a similar manner. I do not, 20 therefore, wish to limit my invention to the purposes set forth nor to the particular construction illustrated but

What I claim and desire to secure by Letters Patent is:

25 1. A cigar box having upwardly tapered notches in opposite sides thereof, an adjustable metallic bed therein having downwardly extending flanges upon each edge, spring wires each secured to the under side 30 of said bed and having its ends extending outwardly through said flange and curved upwardly and inwardly to permit of ready engagement and disengagement with said notches and to readily pass over the inner 35 surface of said box between said notches while being inserted in the box or removed from one position to another and a single ribbon extending between said spring wires

upon the under side of said metallic bed and through the slotted flanges in opposite edges 40 thereof whereby said bed may be raised in said box, substantially as set forth and for the purposes specified.

2. A cigar box having a fixed bottom and provided with upwardly tapered notches in 45 the opposite side walls, an adjustable metallic bed therein provided with fingers, spring wires each fastened to the under side of said metallic bed at its middle point and bent to form resilient catches which project through 50 and have their bearing in the flanges of said metallic bed and a single flat flexible tape extending beneath said metallic bed between said wires and through slots near the edges 55 of said metallic bed and upwardly to permit said bed and its contents to be adjusted upwardly, substantially as set forth and for the purposes specified.

3. In a cigar box having a metallic adjustable bed having downwardly extending 60 flanges upon each edge, two of said flanges being provided with slots and two of said flanges being provided with perforations, wires each fastened to said metallic bed upon the under side thereof near its center 65 and having angular extensions projecting outwardly through said perforations and curved upwardly and inwardly and a flat ribbon extending between said wires upon the under side of said bed and through said 70 slots, substantially as set forth and for the purposes specified.

ALICE W. FALLON.
